UNITED STATES PATENT OFFICE.

GEORGE C. REITH AND GEORGE F. FLADE, OF PHILADELPHIA, PENNSYLVANIA.

COIN-SELECTOR.

973,302.

Specification of Letters Patent. Patented Oct. 18, 1910.

Application filed November 12, 1909. Serial No. 527,639.

To all whom it may concern:

Be it known that we, GEORGE C. REITH and GEORGE F. FLADE, both citizens of the United States, residing in Philadelphia, Pennsylvania, have invented certain Improvements in Coin-Selectors, of which the following is a specification.

This invention relates to that class of apparatus particularly designed for attachment to vending or other machines designed to be automatically set in operation by a coin or token of predetermined denomination and dimensions, and is primarily intended to automatically discard or reject a coin or token of improper denomination or one which is worn beyond a predetermined amount, which is counterfeit, which is of improper dimensions, or which otherwise fails to meet certain definite and predetermined conditions, but will receive or give a certain direction to a proper standard coin.

A further object of the invention is to provide a machine of the type noted which shall be of a simple and substantial construction, shall consist of but relatively few parts, and shall be proof against malicious interference with its operation.

It is also desired to provide a coin selector whose parts shall be so arranged as to not be easily put out of order or require repairs; the invention further contemplating the provision of improved means whereby injury to any of the parts shall be prevented even though slugs, washers or spurious coins of improper dimensions are placed in the machine.

Another object of the invention is to provide means whereby visual or other indication shall be given of the passage of a standard coin through the device and some mechanism operated which shall control the vending or other machine to which said invention is attached.

It is further desired to provide means whereby the sticking of a coin in the machine shall be prevented even though gum or other adhesive has been applied to said coin.

These objects and other advantageous ends are secured as hereinafter set forth, reference being had to the accompanying drawings, in which:—

Figure 1, is a side elevation of the machine. Fig. 2, is a horizontal section on the line *a—a*; Fig. 3, is a rear end elevation

partly in section on the line *b—b*; Fig. 4, is 55 a vertical section on the line *c—c*, Fig. 3. Fig. 5, is a vertical section on the line *d—d*, Fig. 1. Fig. 6, is a horizontal section on the line *e—e*, Fig. 5; Fig. 7, is a detached perspective view illustrating the detail construction of the valve controlling mechanism and certain associated parts, and Fig. 8, is an enlarged vertical section illustrating the detail construction of the slide and certain of its associated parts. 65

In the above drawings, 1 represents a supporting frame having a horizontal base portion 1^a and a vertically extending part 1^b constituting a standard. On the base portion is mounted a dash pot having a cylinder 2, a piston 3 and a spring 4 confined between said piston and the upper head of said cylinder. The lower face of the piston has a packing 5 of leather or other suitable material held in place by a screw 6. 70

At the top of the part 1^b of the frame is mounted a horizontally extending hollow cylindrical structure 7, held to said standard by screws 8, and provided with a slot 9 in its top and a slot 10 in its under side. An 80 operating lever 11 is fulcrumed within the structure 7 by means of a pair of trunnion screws 12 and projects upwardly through the slot 9; being normally inclined to the rear and terminating in a handle or head 85 13. The body of this lever adjacent its fulcrum screws is hollow with its axis extending substantially at right angles to the general line of the handle part thereof, and it contains a plunger 14 between whose inner 90 head and a screw 15 is confined a spring 16, so that said plunger may, under certain abnormal conditions, move into this hollow body rather than break or distort some portion of the device. The rear or outer end of 95 the plunger 14 is connected by a pin 17 both to a link 18, attached by an adjustable screw 19 to the piston 3 of the dash pot, and also to a link 20 connected by a pin 21 to a coin presenting plunger 22. The said plunger is 100 guided within the structure 7 so as to be movable in a substantially horizontal line and has mounted on its rear face a ring 23 of hardened material, such as steel, whose rear edge is sharpened. Said knife edge is 105 of such diameter as to be capable of fitting into the space between the rim and the raised design of the coin which the machine is de-

signed to receive, so as to engage the low lying plane surface of said coin.

The link 20 is preferably made in the shape of a triangular plate with a pin 17 extending through it adjacent to one of its angles and a pin 21 extending through its second angle, while its third angle is so placed as to be capable of engaging a pin 24 guided in a suitable cavity of the plunger 22 so as to be movable parallel to the axis of said plunger. This pin has a longitudinally extending flat portion on one side whose surface is engaged by a spring actuated pin 25 mounted in the plunger 22 so as to prevent said pin from turning, as well as to prevent its having too free a movement. This pin 24 is placed so as to project rearwardly from the lowest portion of the plunger 22 and when a coin is introduced into the machine, it is engaged by and supported upon said pin in front of the knife edge ring 23. The plunger 22 also carries two adjustable screws 26 and 26^a preferably placed adjacent to its sides in a horizontal plane passing through its axis and having their rear ends projecting beyond the rear face of said plunger at such a distance apart as to be capable of receiving between them a coin of the standard diameter and holding it centrally before said plunger 22 upon the pin 24. The top of the plunger has a longitudinally extending slot 27 in which is mounted a lever 28 normally maintained with its rear end elevated by a projection 29 on the operating lever 11. Said rear end is preferably turned down at right angles to its length so as to be capable of passing into the space immediately to the rear of the knife edge ring 23, when said lever is in its lowered position, to positively engage and force down a coin which may have been retained in the rear of said ring owing to its having previously been made sticky by the malicious use of an adhesive. The front end of the lever 28 is of such length as to be engaged by the link 20, when this is raised upwardly by operation of the hand lever 11, as herein-after described.

On opposite sides of the rear end of the structure 7 are two lugs for the reception of screws 30 whereby a block 31 is rigidly supported immediately to the rear of said structure. This block, as shown in Figs. 2 and 4, has a central cylindrical cavity 34 containing a longitudinally movable plunger 32 whose front end is slightly larger in diameter than its body and is made in the form of a circular knife edge 33; there being also in the front face of the block 31 a cylindrical recess concentric with said opening 34. The plunger 32 is normally maintained in a forwardly extended position (Fig. 2) by a spring 35 confined between its head 33 and the bottom of the aforesaid recess in the front face of the block 31, and in

order to retain the plunger 32 in position as well as to limit its movement, I provide a notch 36 in its side and mount a screw 37 in said block 31, so that its end enters said notch.

Concentric with the plunger 32 is a forwardly projecting circular knife edge 38 of the same diameter as the knife edge 33 and like it, capable of engaging the flat face of a coin immediately inside of its rim. The diameter of the knife edge 33 is such that it engages some portion of the raised head of a coin or the wreath, depending upon which face of the coin is presented to it.

The rear face of the block 31 has formed in it a relatively large, vertically extending slot or opening, in which is mounted a rectangular plate 39 held in place by two screws 40. Immediately to the rear of this plate is mounted a slide 41 of rectangular section and like the plate 39, made of hardened steel. Fixed to the rear face of the block 31 is an end plate 42 held in position by screws 43 and of such proportions that the slide 41 is free to move vertically between its front face and the rear face of the plate 39. In order to insure that the slide 41 shall bear against the rear face of the plate 39, there is a recess in the front face of the rear plate 42 in which is mounted a plunger 44 actuated by a spring 45, and in addition there is at the top of the rear plate 42 an adjustable screw 46 provided with a jam nut 47. The plate 39 is provided with a small circular opening 48 and there is a similar opening 49 in the slide 41 which, under certain conditions, may come into line with said opening 48 and with the opening 34 of the block 31.

In the opening 49 is mounted a tumbler in the form of a sleeve 50 within which is placed a cylinder 51 having a head 52 and a longitudinally extending vertical slot 53; the dimensions and construction of these parts being such that said sleeve is free to slide on this cylinder and has a spring 54 mounted between its rear end and the head 52. The front edge of the sleeve 50 abuts upon the rear end of the plunger 32 and its length is such that when said plunger is moved to the rear a predetermined distance, said front edge is brought flush with the front face of the slide 41.

An elongated pin 55 extends centrally through an opening 56 of the plunger 32, through the sleeve 50 and the slot 53 of the cylinder 51; terminating in a threaded end or head 55^a screwed into a suitably threaded opening in the plate 42. The front end of this pin is pointed and is designed to engage the central portion of a coin in order to prevent operation to the machine in the event of said portion of the coin being of more than standard thickness.

On opposite sides of the central opening 48 of the plate 39 are openings 57 in which are mounted headed pins 59 and 59^a each having a spring 58 confined between its head and the front face of the plate 39. The front ends 60 and 60^a of these pins pass through suitable openings 61 in the block 31 in such positions that the first of them may abut upon the pin 26^a when the plunger 22 has been moved rearwardly to the predetermined distance, while the end 60 under similar conditions, is so placed as to engage the rim of a coin presented. The rear ends of these two pins abut upon the front ends 15 of hollow tumblers 62 and 62^a slidably mounted in holes 63 on opposite sides of the central opening 49 in the slide 41. These tumblers or pins are pressed forwardly by springs 64 which also act on hollow plungers 65 to press them against the front face 20 of the rear plate 42.

Immediately above the central opening 49 of the slide 41, and extending through the latter, are two vertically elongated openings 25 66 designed to receive pointed pins 67 whose front ends pass through circular openings 68 in the plate 39 and also through openings 69 in the block 31. The rear ends of these pins are somewhat enlarged and are both rounded so as to loosely fit within semi-spherical recesses 70 in the ends of a transversely extending rocker 71 mounted in a recess 72 formed in the front face of the rear plate 42. A screw 73, having a jam 30 nut 74, extends from the rear face of this plate into said recess so as to regulate the position of said rocker and therefore of the two pins 67. These latter are of such length that they may project through and slightly 35 beyond the plane of the front knife edge 38, so that when a standard coin is introduced and the machine is operated, one of them will always strike the lowest portion of the face of a coin, while the other will 40 strike a raised part of said face; thereby permitting one of them to tilt the rocker 45 71 and project forward the other pin to a predetermined extent. Otherwise if the face of the coin presented is a plane one and both 50 of these pins are brought into engagement therewith, they will both project more than the predetermined amount and thus prevent the operation of the machine; such failure of operation being due to the fact that the 55 plunger 32, as well as the two pins 59 can not be pressed to the rear sufficiently to bring the front edge of the sleeve 50 and front ends of the tumbler pins 62 and 62^a flush with the front face of the slide 41.

60 For the purpose of operating this slide and thereby operating a valve to direct the coin, I hang from the lower end of said slide a relatively heavy weight 75 by means of a link 76; there being also a lever 77 fulcrumed to the structure 7 by a pin 78 and

connected to said slide by a pin 79. Said pin 78, as shown in Fig. 4, is supported on a spring 80 by means of a screw 81, thereby providing a yielding mount for said lever in order to prevent injury in the event of undue pressure being exerted upon said lever. The front end of the latter is turned upwardly as indicated at 82, so as to be capable of being engaged by a cam face 83 on the lower end of the operating lever 11, and 75 by this means, when said operating lever is moved to the front, the lever 77 is released so as to permit the slide 41 to drop if it be free so to do. On the return of said lever under the action of the spring 4 and of the vacuum formed in the dash pot, said cam face, 80 by acting upon the end 82 of said lever 77, raises the slide 41 and with it the weight 75, thereby restoring the various parts of the device to their normal positions. 85

A valve 84 is pivoted to downwardly extending lugs on the block 31 by a pin 85 and is also connected to the lower end of the slide 41 by a pin 86, so that in its normal position it is supported slightly to the rear of 90 a vertical plane passing in front of the knife edge 38. Said valve consists of an open ended conduit whose passage is substantially rectangular in cross section and which when in position to receive a standard coin, drops forwardly so that its front side or edge 87 extends under the space between the two knife edges 23 and 38, while said passage forms a continuation of a chute or conduit 88 for the reception of good or 100 standard coins. In some suitable portion of this chute there is provided an opening 89, in or adjacent to which is mounted a lever having one arm 90 pinned to the link 76 and its other arm 91 extended parallel with, but 105 electrically insulated from, a light spring contact 92. This contact and the lever arm 91 form parts of an electric circuit including a source of current 93, an electromagnet 94, and an indicator or alarm 95, for purposes 110 hereafter noted.

In Fig. 8 is shown in a somewhat exaggerated manner, the construction whereby the machine is enabled to receive and pass standard coins of the proper denomination which 115 however are slightly worn, since unless provision was made for the passage of such coins the machine would discard all but absolutely perfect, new coins.

From Figs. 7 and 8 it will be seen that the 120 front face of the slide 41 is divided by two transverse slots or depressions into three sections 41^a, 41^b, 41^c, of which the first and last lie in the same plane while the second is a predetermined distance to the rear of and 125 parallel with, said plane. The tumbler pins 62 and 62^a, as well as the sleeve 50, pass through this intermediate section 41^b, and when the parts are assembled, there will be a certain predetermined space between the 130

rear face of the plate 39 and the adjacent surface of the section 41^b forming part of the front face of the slide 41.

Under conditions of use it will be understood that the apparatus above described is contained within a closed casing which may be either attached to or form part of a vending or other machine designed to be operated by a coin or token and having a suitable chute or directing device (not shown) whereby such coin may be delivered between the plunger 22 and the block 31. The coin so delivered would be brought to rest and would be supported in a vertical plane by the pin 24, between the rear ends of the screws 26 and 26^a. Since the parts of the device normally occupy the positions shown in full lines in Fig. 4, the forward movement of the operating lever 11, as indicated by the arrow, results in a rearward and then a forward movement of the plunger 22; the first part of which movement, however, is in opposition to the action of the spring 4 and of the suction created by the piston 3 of the dash pot. The said lever and the link 20 together form a toggle for causing this action of said plunger, and the coin which rests immediately to the rear of the knife edge 23, is pushed thereby toward and into engagement with the various pieces of mechanism carried by the block 31 and its associated parts.

The slide 41 is ordinarily locked in its raised position shown, against the downward pull of the weight 75 because of the fact that the tumblers formed by the sleeve 50 and the two hollow pins 62 and 62^a project from it into the openings 48 and 57 of the fixed plate 39. The valve 34 is therefore also held in the position shown in full lines so as to be incapable of guiding a coin, which may be dropped in front of the block 31, into the chute 88.

Assuming that the coin presented to the machine is of standard denomination and is in perfect condition, it will, when the plunger 22 is at the rear end of its rearward stroke, actuate the sleeve 50 and the two pins 62 and 62^a, so as to bring their front edges flush with or slightly in front of the face of the section 41^b of the slide 41. This is accomplished partly by reason of the fact that the two circular knife edges 23 and 38 fit inside of the rim of the coin so as to engage the flat portions of its two faces. Further, the pin 55 barely engages the central portion of the coin so as to permit the wreath or head, as the case may be, to engage the knife edge 33 of the plunger 32 and force this latter to the rear against the action of the spring 35 sufficiently to bring the front edge of the sleeve 50 flush with the front face of the slide 41. One of the pins 67 will also engage the low flat portion of the coin between the annular letter

ing thereof and the head or wreath, while the other will engage such wreath or head, so that said pins will occupy the positions shown in Fig. 6 and permit the coin to move to the predetermined extent to the rear so as to actuate the plunger 32 and its associated parts, as previously described. The pin 59^a engages the rear end of the screw 26^a, and under the conditions above described, forces the corresponding tumbler pin 62^a to the rear sufficiently to bring its front face flush with or at a predetermined distance in front of the surface of the section 41^b of the slide 41, while the front end of the pin 59 is engaged by the rim of the coin and is forced thereby to the rear sufficiently to bring the front face of the tumbler pin 62 into a similar position. If it were not that the surface of the section 41^b of the slide was spaced at some distance from the adjacent face of the plate 39, there could be no variation in any of the dimensions of the coin which the device would pass, but since, as is obvious from Fig. 8, it is not necessary that the front face of any of the tumblers should lie precisely flush with the front face of the slide 41 in order to permit of this latter moving, the machine can be made to pass or receive coins whose dimensions vary within certain predetermined limits. If, for example, the difference in dimensions between a new coin and one which has been worn to the maximum extent consistent with its still passing current at its face value, be assumed to be two-one thousandths of an inch, then the surface of the section 41^b would be ground to lie at a distance of two-one thousandths to the rear of the plane including the sections 41^a and 41^c, so that any coin whose dimensions varied no more than two-one thousandths of an inch from the standard, would still be capable of operating the machine and would be accepted thereby. Any greater variation of said coin would, however, result in its being discarded as hereinafter described. When, therefore, the tumbler pins 62 and 62^a and the sleeve 50 have been brought into such positions that their front faces lie in between the plane of the rear face of the plate 39 and the plane of the section 41^b respectively, all support of the slide 41 is removed and it is free to drop under the action of the weight 75, while the valve 84 is consequently moved by said slide from the position shown in full lines in Fig. 4, to the position shown in the dotted lines. As the plunger 22 is moved rearwardly during the first part of its stroke, the pin 24 is moved frontwardly therein by reason of its engagement with a pin 96 mounted on the front face of the block 31, so that the support of the coin is transferred to said latter pin. As a result, when said plunger begins its forward stroke

due to the pin 17 passing above the line joining the pins 12 and 21, the plunger 32 pushes the coin off of the pin 96 so that it drops into the valve 84, which occupies the 5 position shown in dotted lines in Fig. 4. The falling of the weight also moves the lever arm 90 on its fulcrum, so that the spring contact arm 92 is projected through the opening 89 into the interior of the chute 10 or guideway 88. Consequently when the coin falls down said chute, it strikes said arm 92 and forces it against the arm 91, thus completing the circuit which includes the alarm device 95 such as a lamp or bell 15 and at the same time energizing the electromagnet 94. This latter may be used to release or actuate any desired form of mechanism controlling the vending or other machine to which the invention is attached, 20 though the manner and means of accomplishing this end form no part of the present invention. As the lever 11 is made to continue its movement toward the forward end of its stroke, the end of the link 20 25 adjacent the pin 17 strikes the forward end of the lever 28, thereby forcing its rear end downwardly into the space between the plunger 22 and the block 31, so as to surely force downwardly any coin which may have remained between these members owing to some adhesive having been applied to it. Thereafter said lever is again raised to its normal position by reason of the engagement of its front end by the projection 29 30 on the lever 11. Thus it will be seen that the single forward movement of the operating lever results in a complete reciprocation of the plunger 22 whereby a coin is first presented to the valve controlling mechanism and is then released or discharged therefrom into the valve and coin chute, if said coin be of the proper denomination and sizes.

When the operating lever is released 45 after having been moved forwardly, it is immediately moved to the rear under the action of the spring 4 and the piston 3 of the dash pot, so that the plunger 22 is again moved to the rear and then drawn forwardly to its normal position. While this is occurring, however, the cam projection 33 on the lever 11 engages the end 82 of the lever 77, turning this on its fulcrum pin 78 and raising the slide 41 with the weight 75 50 until the sleeve 50 is brought opposite the opening 48; at which time the spring 54 forces it into said opening, thereby preventing further movement of said slide by locking it to the plate 39. At the same time the pins 62 and 62^a are forced by their springs 64 into the holes 57 and any movement of the lever 77 whereby it would tend to continue raising the slide 41, is taken up by the compression of the spring 80 under the 55 action of the movable fulcrum pin 78. The

upward movement of the link 76 turns the lever formed by the arms 90 and 91 on its pivot, thus moving the spring contact arm 92 out of the chute 88 and permitting the coin to pass down the latter into a suitable 70 receptacle. The coin supporting pin 24 is restored to its normal position by the link 20 which engages its forward end and moves it rearwardly as the plunger 22 makes its second forward movement. 75

If instead of being of the standard dimensions and denomination, the coin placed in the machine is a counterfeit whose central thickness, for example, is less than the standard, the plunger 32 will not be moved 80 to the rear sufficiently when the plunger 22 presents the coin to it, to bring the front edge of the sleeve 50 flush with the front face of the slide 41, so that said slide is not released, and the valve 84, instead of being dropped forwardly under the coin, remains in the position shown in full lines in Fig. 4. Consequently the coin, when released by the plunger 22, falls straight downwardly into the casing or into any 85 suitable chute or receptacle (not shown). Under these circumstances, it is obvious that neither the signal 95 nor the electromagnet 94 is energized, so that the machine to which our invention is connected is not operated or 90 released.

If the coin presented be too thick, it prevents the two circular knife edges 23 and 38 from approaching each other to the predetermined extent. The pin 59^a is therefore 100 moved to the rear by the end of the screw 26^a a distance insufficient to bring the front face of its co-acting tumbler pin 62^a flush with the front face of the slide 41, so that, as before, said slide is not released even 105 though the other elements of the device occupy the proper positions.

If the coin is so worn that its rim is less than a predetermined thickness, the pin 59 is not sufficiently moved to cause its co-acting pin 62 to release the slide, while if the object presented to the machine was in the form of a flat washer, the two pins 67 would both be pushed rearwardly to the same extent. As a consequence, the coin is held 115 away from the block 31 so that neither the sleeve 50 nor the pins 62 and 62^a can be brought to their slide-releasing positions. Similarly, if the coin is not of the correct thickness immediately inside of its rim, the 120 knife edge 38 holds it away from the block 31, with the same result as before noted, so that by proper adjustment the machine can be made so that it will accept or pass no other than perfect coins of the correct denomination. Moreover it is possible to adjust the machine to any degree of sensitiveness, so that it will receive and deliver to the chute 88 standard coins which are but slightly worn, while rejecting coins worn to such an 125 130

extent as to be unfit for circulation, as well as counterfeits, slugs, washers, and the like. For purpose of adjustment, the screw 46 may be moved in or out to permit the slide 41 to move more or less loosely in its guideway, and similarly the screw 73, as well as the screws 26, may be adjusted to accomplish the same end.

It will be noted that the cylinder 53, as well as the hollow plungers 65, pass completely through the slide 41 so as to abut upon the front face of the rear plate 42, with the result that there is no force acting upon said slide to move it rearwardly from the plate.

Under normal operating conditions the pointed pin 55 is not employed, but if for any reason it be desired that the coins operated on by the machine shall be directed to the chute 88 only when they are so delivered to the machine that the face bearing the head or figure is toward the front thereof, said pin 55 is projected forwardly by means of its screw so that if that face of the coin bearing the head be toward the rear of the machine, said head would be engaged by the point of the pin, which would thus hold the coin away from the knife edge 38 so that it would fail to move the tumbler 62^a and the sleeve 50 sufficiently far to the rear to free the slide 41.

By the use of the spring 16, the danger of injury to the machine owing to the presentation to it of coins or slugs of more than proper thickness is prevented, since this spring allows the plunger 22 with the link 20 and plunger 14 to yield under such conditions, as the operating lever is pulled to the front. Again, any danger or damage to the machine due to the sudden release of the lever from its full forward position is prevented by means of the dash pot 2, since even though the spring 4 tends to violently return the various parts of the machine to their normal positions, their movement is slowed down by the action of the piston 3; it being noted that the screw 19 may be adjusted to vary the volume of the air between the bottom of the dash pot and the piston thereof.

Of course if the machine is designed to operate solely on supposedly perfect coins so as to detect any imperfection in minting, the slide 41 is so made that the face of its section 41^b is coincident with the plane of the sections 41^a and 41^c, and therefore virtually in contact with the rear face of the plate 39.

We claim:

1. The combination in a coin selector; of a coin directing means; selective controlling mechanism therefor; means, including an operating member, for presenting a coin to and then releasing it from said mechanism; and a device for causing a single movement of said operating lever to result in a com-

plete actuation of said coin presenting and releasing means.

2. The combination, in a coin selector, of a coin directing valve; selective controlling mechanism therefor; means for presenting a coin to said mechanism; an operating member for said means; and means for causing a movement of said member in one direction to present a coin to and then release it from said valve controlling means. 75

3. The combination, in a coin selector, of a coin directing valve; selective controlling mechanism therefor; yielding means for presenting a coin to said mechanism; an operating member for said means; and means for causing a movement of said member in one direction to present a coin to and then release it from said valve controlling means. 80

4. The combination, in a coin selector, of a coin directing valve; selective controlling mechanism therefor; a device for presenting a coin to and subsequently releasing it from said mechanism; said device including an operating member; a coin engaging member; and a connecting device for transforming a movement of the operating member in one direction into two movements in opposite directions of the coin engaging member. 85

5. The combination, in a coin selector, of a coin directing valve; selective controlling mechanism therefor; and a device for presenting a coin to and then releasing it from said mechanism; said device including an operating member, a coin engaging member, and a toggle connecting said members. 90

6. The combination, in a coin selector, of a coin directing valve; selective controlling mechanism therefor; and a device for presenting a coin to and then releasing it from said mechanism; said device including an operating member, a coin engaging member, and a yielding toggle connecting said members. 100

7. The combination, in a coin selector, of a coin directing valve; selective controlling mechanism therefor; means, including an operating member, for presenting a coin to and subsequently releasing it from said mechanism by a movement of said operating member in one direction. 110

8. The combination in a coin selector of a valve; actuating means therefor including a bodily movable member; selective locking means normally holding said member from moving; and means for presenting a coin to said locking means. 120

9. The combination in a coin selector of a valve; actuating means therefor including a longitudinally movable slide; selective locking means normally holding said slide from moving; and means for presenting a coin to said locking means. 125

10. The combination in a coin selector, of a valve; actuating means therefor including a bodily movable member; a tumbler and a 130

structure co-acting therewith, for normally preventing movement of said member; means for presenting a coin to the selector; and means for transmitting movement from 5 the coin to the tumbler.

11. The combination in a coin selector of a valve, means for moving said valve; locking mechanism normally preventing movement of said means; means including an 10 operating member for presenting a coin to the locking mechanism; and a device, actuated by the operating member, for restoring the valve moving means to its normal position after it has moved therefrom.

15 12. The combination in a coin selector of a valve; a weight actuated slide for moving the same, locking means normally holding said slide in an elevated position; means including an operating member for presenting

20 a coin to said locking means; and means actuated by said operating member for restoring the slide to its normal position after it has moved therefrom.

13. The combination in a coin selector of a 25 supporting structure; a valve; a longitudinally movable slide connected thereto; a tumbler for locking said slide to the supporting structure; means including an operating member for presenting a coin to said tumbler; and a lever operatively connected to the slide and placed to be actuated by the operating lever, for restoring said slide to its normal position after it has moved therefrom.

35 14. The combination in a coin selector of a valve; actuating means therefor including a movable member; locking means for said member; a plunger for presenting a coin to said locking means; actuating means for 40 the plunger including an operating lever; with a yieldingly supported lever connecting the operating lever and said movable valve actuating member for returning the latter to its normal position.

45 15. The combination in a coin selector of a coin directing means; actuating means therefor capable of being set in operation by a standard coin; mechanism for presenting a coin to said actuating means, and a movement-retarding device connected to said mechanism.

50 16. The combination in a coin selector of a coin directing means; actuating means for said coin directing means; a device normally locking said actuating means; a plunger for presenting a coin to said locking device; an operating member connected to transmit motion to said plunger; and movement-retarding means for said operating member.

60 17. The combination in a coin selector of a coin directing means; normally locked actuating means for said coin directing means; a device normally locking said actuating means; a plunger for presenting a coin to 65 said locking device; an operating member

connected to transmit motion to said plunger; and a dash pot for retarding the movement of said operating member.

18. The combination in a coin selector of coin directing means; controlling mechanism therefor; means for presenting a coin to said controlling mechanism; and a device for positively removing said coin after such presentation.

19. The combination in a coin selector of coin directing means; controlling mechanism therefor; means for presenting a coin to said controlling mechanism; and a device controlled by the coin presenting means for positively removing said coin after its presentation to said controlling mechanism.

20. The combination in a coin selector of coin directing means; controlling mechanism for said means; a plunger for presenting a coin to said mechanism; operating means for actuating said plunger; and a device actuated by said operating means for positively forcing a coin away from the plunger after it has been presented thereby to the controlling mechanism.

21. The combination in a coin selector of coin directing means; mechanism controlling the operation thereof; a member for presenting a coin to said mechanism; operating means for actuating said member; and a lever actuated by said operating means and in position to positively force a coin away from the member after it has been presented thereby to the controlling mechanism.

22. The combination in a coin selector of coin directing means; controlling mechanism for said means; the same including a coin-actuated, tumbler-governed lock having a device for permitting its release by a coin whose dimensions are within predetermined amounts of the standard measurements; and means for presenting a coin to said lock.

23. The combination in a coin selector of a fixed structure; a movable structure immediately adjacent to but having a portion spaced away from said fixed structure, actuating means for the movable structure; co-acting locking tumblers mounted in said structures and constructed to have their co-acting faces brought into the space between the structures by the presentation to them of a standard coin; means for presenting a coin to actuate said tumblers; and coin directing means controlled by the movable structure.

24. The combination in a coin selector of a fixed structure; a movable structure having a portion of its surface spaced away from said structure; locking means including two co-acting pins mounted in said structures and so formed that their abutting faces may be brought into the space between the structures when said pins are actuated by a standard coin; means for actuating the mov-

- able structure when the pins permit of its movement; coin directing means controlled by said movable structure; and means for presenting a coin to the locking means.
- 5 25. The combination in a coin selector of a supporting structure; a slide movably mounted therein and having a portion of its surface spaced a predetermined distance away from the adjacent surface of said structure; locking means for the slide including two co-acting tumblers proportioned to have their co-acting faces brought into the space between the slide and the supporting structure by a coin whose dimensions are within predetermined amounts of a standard; coin directing means controlled by the slide; and means for presenting a coin to the locking means.
- 20 26. The combination in a coin selector of a supporting structure; a movable slide; spring actuated tumblers with means co-acting therewith for normally locking said slide to said structure and mounted within the slide so as to exert pressure solely on the supporting structure; means for presenting a coin to actuate said tumblers; and coin directing means actuated by said slide.
- 25 27. The combination in a coin selector of a supporting structure; a movable structure having means for normally locking it thereto; coin directing means controlled by said movable structure; a plunger for presenting a coin to said locking means; and an operating member for the plunger including connecting means for limiting the movement of said plunger to a predetermined amount.
- 30 28. The combination in a coin selector of a fixed structure; a movable structure; means normally locking said structures together; means for presenting a coin to said locking means to actuate the same under predetermined conditions; coin directing means controlled by the movable structure; and an electrical circuit including a contact placed to be controlled by a coin.
- 35 29. The combination in a coin selector; of a fixed structure; a movable structure; means normally locking said structures together; means for presenting a coin to said locking means to actuate the same under predetermined conditions; coin directing means controlled by the movable structure; and an electrical circuit including a contact placed to be controlled by a coin; said contact being movably supported and connected to the movable structure so as to be projected into or removable from the path of the coin when said movable structure is actuated.
- 40 30. The combination in a coin selector of coin directing means; controlling mechanism for said means including a locking device; means for presenting a coin to said locking device; and means for preventing release of the locking device by a coin un-
- 45 less the head of said coin is presented in a predetermined position relative to the locking device.
- 50 31. The combination in a coin selector of coin directing means; controlling mechanism therefor including a movable member, and means normally locking said member from movement; means for presenting a coin to the locking means; and a pin in position to prevent the coin from actuating the locking means unless a certain face of said coin is presented to the same.
- 55 32. The combination in a coin selector of coin directing means; controlling mechanism therefor including a movable member and locking means for normally preventing movement of said member; means for presenting a coin to said locking means; and two co-acting members placed to prevent the release of the locking means by a coin unless one of said members strikes a low portion of a coin at the same time the second strikes a high part thereof.
- 60 33. The combination in a coin selector of coin directing means; controlling mechanism therefor including a movable member and locking means for normally preventing movement of said member; means for presenting a coin to said locking means; and a rocker having two pins placed to prevent release of the locking means by a coin unless one of said pins strikes a low portion of the face of said coin and the other simultaneously strikes a high portion thereof.
- 65 34. The combination in a coin selector of coin directing means; controlling mechanism for said means; means for presenting a coin to said mechanism, the same including a plunger; an operating member; and a supporting pin for holding a coin between the plunger and the mechanism; with means for freeing the coin from said pin after its presentation to said mechanism.
- 70 35. The combination in a coin selector of a device for separating standard from spurious coins; a coin chute connected thereto; an electric circuit including an electromagnet and a contact member; with means for temporarily projecting said contact into the coin chute so that the electric circuit will be closed by the coin delivered thereto.
- 75 36. The combination in a coin selector of a device including a movable element for separating spurious from standard coins; a coin chute; a spring contact mounted adjacent thereto and connected to said movable element so as to be movable into and out of the chute thereby; with an electric circuit, including a current actuated device, connected to said contact.
- 80 37. The combination in a coin selector of a supporting structure; a coin directing device; controlling mechanism therefor, including a movable member; and means for normally locking said member to said struc-

ture; means for maintaining the movable member pressed against a definite part of said supporting structure, and means for presenting a coin to the locking means.

5. 38. The combination in a coin selector of a supporting structure having a plane vertical surface; a slide movable adjacent to said surface; means tending to move said slide; a series of sets of tumblers with 10 operating means for normally locking the slide to the supporting structure; means for presenting a coin to said tumblers; coin directing means actuated by said slide; and

means for preventing movement of the tumblers, by a coin, to their slide-releasing positions, unless said coin is of standard dimensions.

In testimony whereof, we have signed our names to this specification, in the presence of two subscribing witnesses.
